UNITED STATES PATENT OFFICE.

ERASTUS E. WINKLEY, OF LYNN, MASSACHUSETTS, ASSIGNOR TO UNITED SHOE MACHINERY CORPORATION, OF PATERSON, NEW JERSEY, A CORPORATION OF NEW JERSEY.

MATRIX ROLL AND METHOD OF MAKING THE SAME.

Application filed December 19, 1921. Serial No. 523,527.

To all whom it may concern:

Be it known that I, ERASTUS E. WINKLEY, a citizen of the United States, residing at Lynn, in the county of Essex and State of Massachusetts, have invented certain Improvements in Matrix Rolls and Methods of Making the Same, of which the following description, in connection with the accompanying drawings, is a specification, like reference characters on the drawings indicating like parts in the several figures.

The invention relates to a roll or segment having a matrix or mould on its periphery and to a method of and apparatus for making such rolls or segments.

While the invention is applicable to matrix rolls adapted for various uses it has been developed with special reference to sole shaping matrix rolls for leveling shoe soles and will be further explained as applied to such rolls.

In order that the sole of a lasted shoe may be accurately shaped by a leveling roll which rolls along the sole it is desirable that the roll be provided on its periphery with a matrix corresponding to the shape which is to be given to the sole. It is also desirable that the pressure applied by the roll to the sole, or at least to the comparatively flat portions thereof such as the forepart, should be a rolling pressure applied without lengthwise slip. A matrix roll which is well adapted for applying such pressure may be produced in accordance with a feature of the present invention by impressing a pattern form corresponding to a leveled sole in the periphery of a body of plastic material while rotating the body about an axis which travels relatively to the pattern in a

path parallel to the surface of the pattern along its medial line and at a rate equal and opposite to the surface speed of the moulded plastic at its final line of contact with the form, and thereafter reproducing in im-

plastic material the cylindrical matrix thus generated. By this method of forming the matrix the shape to be given the sole is developed on a surface of revolution, on approximately such a surface concentric with the leveling roll, and the matrix may be given a rolling contact with the sole to be leveled without material slip, by so rotating the roll as it progresses along the sole

that its surface speed at the line of contact with the sole is equal and opposite to the rate of progression of the roll along the sole.

In leveling shoes having a well defined line of demarcation between two portions of the sole as, for instance, in leveling high arch shoes having shanks or in leveling spring heel shoes, it may be desirable to develop that portion of the matrix which corresponds to the sharply inclined portion of the sole adjoining the ball line in high arch shoes or adjoining the heel line in spring heel shoes on a surface which bulges abruptly from the cylindrical surface on which the forepart of the heel of the matrix is developed, in order that the pressure applied by the roll to the inclined surface may be more nearly normal to such surface. Such parts of the matrix may be generated by causing the axis about which the plastic body rotates as it progresses along the pattern to follow a path not parallel but bearing a predetermined relation to the surface of the pattern along its medial line.

In forming either the cylindrical concentric part of the matrix or the eccentric bulging part the method is generically the same since in either case the matrix is generated by the pattern form in a plastic material which is rotated about an axis having a relative movement lengthwise of the form the rate of which bears a predetermined relation to the speed of rotation and the path of which bears a predetermined relation to the surface of the form along its medial line, the path of movement depending upon the action which it is desired that the matrix of the leveling roll shall have as the roll travels along the shoe sole.

The invention is illustrated in the drawings in connection with the making of a leveling roll intended for use in leveling shoes having high arch shanks and will be further explained in this connection.

In the drawings Fig. 1 is a plan view of the apparatus which may be conveniently used in developing a matrix in the periphery of a plastic body, Fig. 2 is a vertical sectional elevation of the same, Fig. 3 is a vertical transverse sectional view through the axis of the plastic body carrying roll, Fig. 4 is a detailed view of the core of the roll, Fig. 5 is a sectional view on line 5—5,

Fig. 3. Fig. 6 is a detail view showing the manner in which the core is removed from the moulded plastic, Fig. 7 is an end view of the moulded plastic removed from the roll, 5 Fig. 8 is an elevation of the same, Fig. 9 is a sectional view on line 9—9, Fig. 8, Fig. 10 is an end elevation of the leveling roll and Fig. 11 is a sectional view on a line corresponding to line 9—9 of Fig. 8.

10 The leveling roll shown in Figs. 10 and 11 is provided on its periphery with a matrix having a forepart 2 developed on a surface of revolution, the axis of which coincides with the axis of the roll. The 15 matrix also has a shank portion 4 which departs from the contour of the forepart and then gradually approaches or merges with a surface of revolution 6 near or at the heel breast line. In making this roll 20 by the method of the present invention a facsimile of the matrix on the roll is first generated in the periphery of a roll of plastic material by a facsimile of the sole to be produced and the matrix thus generated is then reproduced in implastic material as for instance by utilizing the generated matrix as a pattern from which to 25 cast a metal leveling roll.

The matrix may be conveniently generated in the plastic material by the apparatus shown in Figs. 1, 2 and 3. As here shown a pattern form 8 which is a duplicate or facsimile of that to be given to a shoe sole by the completed leveling roll is sup-

30 ported between two guide plates 10, the upper edges of which form guides which support and guide a plastic carrying roll which travels over the pattern form. The pattern may be a leveled shoe sole or a form having the shape of a leveled shoe sole. The plastic body carrying roll is provided with cylindrical heads 12 which rest on the guides and with a tapered and ribbed core 14 secured to the heads by screws 16. The 40 heads are provided on their outer ends with gears 18, the pitch surfaces of which coincide with the cylindrical surfaces of the heads and these gears are engaged by racks 20 arranged along the outer sides of the guide plates. The racks are pivotally supported at one end so that they may rise and fall with the roll as it rolls along the guides and they are held in engagement with the gears by guide stirrups 22 hung on 45 trunnions 24 on the heads. The parts are maintained in proper relation by a shaft 26 passing through the roll and having retaining collars 28 secured to its ends outside the rack supporting stirrups.

50 To generate a matrix the space about the core 14 and between the heads 12 is filled with plastic material 30 which projects beyond the peripheries of the heads and then the roll is moved along the guides while 55 being maintained in engagement therewith

by downward pressure applied to the roll. As the roll travels along the guides it is rotated by its engagement with the racks and the pattern is pressed into the plastic material and generates a matrix therein. 70 The shape of the matrix generated will depend on the shape of the guides which determine the path of travel of the axis of the roll with relation to the surface of the pattern. As shown those parts of the guides 75 which support the roll during its travel over the forepart of the pattern are in cylindrical surface containing the forepart surface of the pattern sole so that this surface will always lie in the pitch surface of the gears 80 as they roll past it. The forepart 32 of the matrix will, therefore, be generated on a cylindrical surface concentric with the roll and by a rolling contact between the finely moulded plastic and the pattern. Those 85 parts of the guides 34 which support the roll as it passes from the forepart to the shank rise above the surface of the pattern as shown in Fig. 2, and then gradually return to said surface so that as the roll rolls over 90 this part of the guides the pattern will generate a bulging eccentric shank 36 for the matrix which gradually approaches or returns to a surface concentric with the matrix forepart. During the travel of the 95 roll over the pattern the plastic material may be pressed and banked up about the marginal edges to secure a well defined impression of the pattern.

After the matrix has been thus generated 100 in the periphery of the plastic roll by the facsimile of the shoe sole the plastic material is removed from the roll by detaching the heads 12 and withdrawing the tapered core and ribs. The plastic body will then be in the form of a sleeve such as shown in Figs. 7, 8 and 9 provided on its periphery with the generated matrix. This sleeve may then be utilized as a pattern in casting the leveling roll shown in Figs. 10 and 11. 105 This roll may be provided at its ends with attached gears similar to the gears 18 and may be rolled over the sole to be leveled while the gears are maintained in engagement with racks similar to the racks 20 and 110 when so used the concentric part 2 will apply a rolling pressure without material lengthwise slip to the forepart of the sole and then as the ball line is reached the bulging shank portion 4 will swing quickly in 115 against the sharply inclined surface of the shank near the ball line and in crowding the axis of the roll away from the surface of the sole will apply its pressure in a direction approximately normal to this surface and at the same time will tend to draw the sole somewhat toward the ball line, thereby tending to maintain a well defined line of demarcation between the shank and forepart while effectively shaping the shank. 120 125 130

While the invention has been shown and described as applied to the making of a sole leveling matrix roll it will be understood that it is not limited in its application to the making of such rolls. For instance, a matrix such as indicated at 38 in Fig. 8 corresponding to the marginal outline of the pattern may be generated for use as a cam pattern for controlling the movement of some instrument which should have a path of movement corresponding to the outline of the sole. It will also be understood that the broader features of the invention may be utilized with advantage in generating and making matrix rolls for any use requiring an accurately shaped matrix on the periphery of the roll.

What is claimed is:

1. A step in the method of making matrix rolls which consists in impressing a pattern form in the periphery of a plastic body while rotating the body and giving its axis of rotation a pre-determined path of travel with relation to the pattern.

2. The method of making matrix rolls which consists in impressing a pattern form in the periphery of a plastic body while rotating the body and giving its axis of rotation a predetermined path of travel with relation to the pattern, and reproducing the generated matrix in implastic material.

3. The method of making matrix rolls which consists in generating a matrix in the surface of a roll having a plastic periphery by a facsimile of the shape to be produced by the matrix roll, and then reproducing the generated matrix in implastic material.

4. The method of making matrix rolls which consists in impressing a pattern form in the periphery of a body of plastic material which is rotated about an axis having a relative movement along the form, the rate of which bears a predetermined relation to the speed of rotation and the path of which bears a predetermined relation to the surface of the form along which the axis progresses, and thereafter reproducing the generated matrix in implastic material.

5. A step in the method of making matrix rolls which consists in impressing a pattern form in the periphery of a body of plastic material while rotating the body about an axis which progresses along the pattern in a path parallel to its surface and at a speed equal and opposite to the surface speed of the moulded plastic material at its final line of contact with the pattern.

6. The method of making matrix rolls which consists in impressing a pattern form in the periphery of a body of plastic material while rotating the body about an axis which progresses along the pattern in a path parallel to its surface and at a speed equal and opposite to the surface speed of the moulded plastic material at its final line

of contact with the pattern, and reproducing the generated matrix in implastic material.

7. A step in the method of making matrix rolls which consists in rolling a body of plastic material over a pattern form while supported by a cylindrical surface which rolls along a surface corresponding in outline to or bearing a predetermined relation to a selected line of the form.

8. A step in the method of forming matrix rolls which consists in impressing a pattern form in a plastic body while rolling the body along the pattern with a motion corresponding to the rolling of a concentric cylindrical surface along the medial line of the form or a line bearing a predetermined relation to such medial line.

9. A step in the method of making matrix rolls which consists in rolling a plastic body along a pattern form while maintaining the axis of the body at a uniform distance from the surface of the pattern.

10. A step in the method of making matrix rolls which consists in generating a matrix in the surface of a roll having a plastic periphery by a pattern which is a facsimile of a shoe sole.

11. A method of making shoe leveling matrix rolls which consists in generating a matrix in the surface of a roll having a plastic periphery by a pattern which is a facsimile of a leveled sole, and reproducing the generating matrix in implastic material.

12. The method of making matrix rolls which consists in impressing a pattern which is a facsimile of a shoe sole in the periphery of a body of plastic material while rotating the body about an axis which progresses along the pattern in a path parallel to the medial surface of the pattern and at a rate of speed equal and opposite to the surface speed of the moulded plastic material at its final line of contact with the pattern, and reproducing in implastic material the cylindrical matrix thus generated.

13. A method of making sole leveling matrix rolls which consists in rolling a plastic body over a facsimile of a shoe sole to generate that part of the matrix corresponding to a comparatively flat part of the sole on a cylindrical or concentric surface and that part of the matrix corresponding to an adjoining sharply inclined part of the sole on a bulging eccentric surface, and reproducing the generated matrix in implastic material.

14. A sole leveling roll provided on its periphery with a matrix having a part developed on a concentric surface and a part developed on a bulging surface projecting beyond said concentric part.

15. A sole leveling roll provided on its

periphery with a matrix having a forepart developed on a concentric surface and a bulging shank projecting beyond the forepart.

5 16. In a machine of the class described, means for supporting a form, a guide having a predetermined relation to the contour of the form, and a holder arranged to support a plastic body, and to be traversed 10 along the guide over the form.

17. In a machine of the class described, means for supporting a form, a guide having a predetermined relation to the contour of the form, a holder arranged to support a plastic body, and to be traversed 15 along the guide over the form, and means for rotating the holder as it passes over the form.

18. In a machine of the class described, 20 a form having the contour of a shoe to be leveled, a guide having a predetermined relation to the vertical profile of the form, and a holder arranged to support a mass of plastic material and to roll along the guide.

25 19. In a machine of the class described, a form having the contour of a shoe to be leveled, a guide having a predetermined relation to the vertical profile of the form, a holder arranged to support a mass of 30 plastic material and to roll along the guide, and means for rotating the holder as it rolls along the guide, at a speed having a predetermined relation to its natural speed of rotation along the guide.

35 20. In a machine of the class described, a form having the contour of a shoe to be leveled, a guide having a predetermined relation to the vertical profile of the form, a

holder arranged to support a mass of plastic material and to roll along the guide, a gear 40 on the holder having its pitch line in registration with the guide, and a rack arranged to drive the gear as the holder rolls over the guide.

21. In a machine of the class described, a 45 form having the contour of a shoe to be leveled, a guide having a predetermined relation to the vertical profile of the form, a holder arranged to support a mass of plastic material and to roll along the guide, a gear 50 on the holder having its pitch line in registration with the guide, and a rack arranged to drive the gear as the holder rolls over the guide, said rack being supported by the holder.

55 22. In a machine of the class described, a form having the contour of a shoe to be leveled, a guide having a predetermined relation to the vertical profile of the form, a holder arranged to support a mass of plastic material and to roll along the guide, a gear 60 on the holder having its pitch line in registration with the guide, and a rack arranged to drive the gear as the holder rolls over the guide, said rack being pivoted on the main 65 frame of the machine and arranged to follow the holder as it rolls over the guide.

70 23. A form having a portion with a profile shaped like that of the forepart of a shoe to be treated, combined with a portion having a vertical profile projecting substantially above the profile of the shank portion of the said shoe.

In testimony whereof I have signed my name to this specification.

ERASTUS E. WINKLEY
